UNITED STATES PATENT OFFICE.

JOSEPH ERRETT, OF CLEVELAND, OHIO.

PLATFORM-GEAR FOR VEHICLES.

1,076,202.

Specification of Letters Patent.

Patented Oct. 21, 1913.

Application filed June 1, 1910. Serial No. 564,437.

To all whom it may concern:

Be it known that I, JOSEPH ERRETT, a resident of Cleveland, in the county of Cuyahoga and State of Ohio, have invented a new and useful Improvement in Platform-Gears for Vehicles, of which the following is a full, clear, and exact description, reference being had to the accompanying drawings, forming part of this specification, in 10 which—

Figure 1 is a front elevation of portions of a platform gear embodying one form of my invention. Fig. 2 is a perspective view of one of the truss rod securing plates. Fig. 3 15 is a perspective view of the top hound plate of Fig. 1. Fig. 4 is a detail perspective view showing a modified form of said plate and of the truss rod. Fig. 5 is a view similar to Fig. 1, but showing another form of 20 my invention. Fig. 6 is a perspective view of the lower hound plate of Fig. 5; and Fig. 7 is a perspective view of one of the spring shackle irons of Fig. 5.

My invention has relation to front or 25 platform gears for vehicles of the general type shown in my Patent No. 922,869 of May 25, 1909; and is designed to provide an improved construction and arrangement of the splinter bar truss or braces which will 30 permit of adjustment to take up any settling of the gear; which will provide a strong and durable construction; and which will avoid expense of forging and fitting of the parts.

The nature of my invention will be best 35 understood by reference to the accompanying drawings, which will now be described, it being premised, however, that various changes can be made in the details and construction of the parts, without departing 40 from the spirit and scope of my invention, as defined in the appended claims.

Referring first to the form of my invention shown in Figs. 1, 2 and 3, the numeral 2 designates the splinter bar, which in this 45 form extends transversely underneath the pole hounds. Secured to the under sides of the end portions of the splinter bar are the spring shackle irons 4. Secured to the upper side of the end portions of said bar are 50 the plates or irons 5, each of which may carry a step 6, and which also preferably have the portions 7 adapted to be secured to the usual side hounds. Each of these plates or irons 5 is also formed on its upper surface with a sleeve portion 8 having an opening therethrough and through the iron to

receive the end portion of a truss rod 9. 10 is a combined hound and brace plate which is secured to the upper side of the pole hounds 3 and has the depending brace portions 11 which are secured to the splinter bar at 12 at each side of the pole hounds. This plate 11 has a central connecting portion 11^a with slotted end portions 11^b which are adapted to receive the heads or nuts 9^a 60 of the truss rods 9. In the construction shown at Fig. 1, one of these truss rods 9 extends through the end portion of the splinter bar, the sleeve portion 8 of the plate or iron 5, and thence to the plate 11 with its 70 inner end passing through and engaged with the slotted portion 11^b of the plate 11. The outer end of each of these truss rods is secured by a nut 13 having a bearing against a depending lug 14 on the plate 5, which lug 75 fits against the outer end of the splinter bar.

Instead, however, of using two short truss rods as shown in Fig. 1, a continuous truss rod 15 may be employed, as shown in Fig. 4. In this form the central portion 11^c of the 80 upper hound plate is provided with an extended transverse bearing for the central portion of the truss rod.

Fig. 5 shows my invention applied to a type of gear in which the splinter bar 2^a 85 instead of extending transversely underneath the pole hounds 3^a extends over the same. In this form of my invention a plate 16, which corresponds to the plate 11 first described, is secured to the under side of the 90 pole hounds with lateral bracing portions 16^a secured to the splinter bar at opposite sides of the pole hounds. The plate 16 has depending slotted lugs or hooks 16^b which are engaged by heads or nuts 17^a on the 95 inner ends of truss rods 17, which correspond to the truss rods 9 shown in Fig. 1, except that they are arranged underneath the splinter bar and pole hounds, and their under portions are extended upwardly 100 through the spring shackle irons 18 and through the end portions of the splinter bar, being secured by nuts 19 at their outer ends to seat against the upturned lips or lugs 19^a of the shackle irons. In this form the 105 shackle iron is made with a sleeve portion 18^a through which the truss rod passes.

It will be obvious that instead of the two short truss rods 17, I may employ a continuous truss rod, as employed in Fig. 4, but extending below the pole hounds. These truss rods can be readily adjusted to take up any

settling of the gear, thus avoiding the necessity for taking the entire gear apart and putting in a new splinter bar to which the irons must be refitted.

5 The combined hound plates and braces form an additional truss support for the splinter bar and also an efficient bearing for the truss rod or rods. It also effectually serves to prevent spreading of the pole hounds.

10 The term "truss rod," as used in the claims, is intended to refer either to a continuous rod, such as shown in Fig. 4, or, to a divided rod, such as shown in Figs. 1 and 5.

15 What I claim is:

1. In a platform gear for vehicles, a trussed splinter-bar having a step-iron secured to the end portion thereof, said iron having a projecting sleeve portion formed with an oblique opening therethrough to receive the splinter-bar truss rod; substantially as described.

2. In a platform gear for vehicles, a trussed splinter-bar having a step-iron secured to the end portion thereof, said iron having a projecting sleeve portion formed with an oblique opening therethrough to receive the splinter-bar truss rod, and also 30 having a depending lug to receive the end of the truss rod and to form a seat for the

securing nut thereof; substantially as described.

3. In a platform gear for vehicles, a trussed splinter-bar, and an end iron secured thereto, said iron having an oblique projecting sleeve portion formed with an aperture therethrough to receive the splinter bar truss rod; substantially as described.

4. In a platform gear for vehicles, a transverse splinter bar having a horizontal portion at each end, each of said horizontal portions having an opening entering the same at an angle and thence extending in a more nearly horizontal direction, a plate secured to each end portion of the splinter bar and having a sleeve portion whose opening is in line with the opening in the end portion of the bar, and a truss rod having its ends extending outwardly through the respective sleeve portions and openings and having securing means at its ends seating against the ends of the bar, the end portions of said truss rod being bent after they enter the said openings to a more nearly horizontal direction, substantially as described.

In testimony whereof, I have hereunto set my hand.

JOSEPH ERRETT.
